UNITED STATES PATENT OFFICE.

CARLTON E. CURRIE, OF LOS ANGELES, CALIFORNIA.

ADJUSTABLE POSITIVE-GRIP STEEL-BEAM HOOK.

Application filed July 28, 1926. Serial No. 125,423.

This invention relates to an adjustable positive grip lifting device which has been primarily designed for lifting structural steel members such as I beams, T's, H columns, 5 angles and the like.

The primary object of the invention is to provide an improved device of this character which is adjustable and which is engageable upon the flange of a structural steel member 10 which will permit the structural steel member to be lifted thereby very easily without danger of slipping.

Another object of the invention is to provide a device which may be easily and quickly applied to a structural steel member at approximately its center so that it may be lifted by a hoist into the desired position.

With the foregoing and other objects in view which will be made manifest in the following detailed description and specifically pointed out in the appended claims, reference is had to the accompanying drawings, wherein

Figure 1 is a perspective view of the device shown in applied position preparatory to lifting,

Fig. 2 is a horizontal section taken substantially upon the line 2—2 of Figure 1.

Referring to the accompanying drawings 20 wherein similar reference characters designate similar parts throughout, the improved hook consists of a body providing two arms 10 and 11 which are rigidly secured together and which are arranged at approximately right angles to each other. In the upper arm 10 there are formed a plurality of apertures 12 which extend transversely through this arm providing for the insertion of the hook H which may be on a hoist at different points 25 along this arm which are remote from the longitudinal axis of the arm 11. The top of the arm 10 upon which aperture 12 may be rounded, is clearly shown upon the drawing, to facilitate the insertion of the hook.

The body between the apertures 12 and at the juncture between the two arms may be recessed, thus saving metal and making the hook fairly light, although the strength of the body will not be decreased thereby.

On the side 13 of the lower arm 11 which is exposed toward the upper arm 10, there is formed a shoulder 14 on which the bottom edge of the I beam I or similar structural steel member may be positioned. A slot 15 50 is formed in the arm 11, having one end ter-

minating on the side 13 and this slot extends a considerable distance along the arm. The sides of the arm adjacent the slot are preferably thickened, so as to make this arm equally strong.

A locking member 16 is slideable in the slot 15 and has both ends widened, as shown in Fig. 2, to prevent its withdrawal from the slot. The end of the locking member, which is on the side 13 of the arm 11, is angular in 60 form, as indicated at 17, extending toward the shoulder 14.

The operation of the improved device is as follows:

When it is desired to lift a structural steel member such as the I beam I, the hook is so positioned with respect to one of the flat sides of the I beam that the bottom rests on the shoulder 14. The locking member 17 is raised to the top of the slot 15 and when the arm 11 is positioned against the side of the I beam the locking member is pressed downwardly or allowed to fall downwardly over the top edge of the I beam. When this is done the hoist may be operated to lift the I beam to the desired location. During the lifting, the weight of the I beam on the hook will cause the hook to swing downwardly with respect to the hook H so that the I beam will be resting to a great degree directly against the face 13. It will not slip off of this face because of the shoulder 14 and the locking member will serve to maintain the I beam against the face 13.

The locking member also serves an additional function. In the event that the improved device is not positioned at the center of the I beam, the I beam would normally tend to slip endwise from between the shoulder 14 and the locking member. There is a small clearance between the enlarged ends of the locking member and the edges of the arm 11, and this clearance enables the locking member to swing slightly so as to bind and prevent the locking member from being forced upwardly within the slot due to an attempted tilting action of the I beam. In this way the locking member cannot be forced upwardly and its edges will engage upon the edge of the I beam and effectively prevent the I beam from slipping out of the device.

From the above described construction it will be appreciated that an improved positive grip is provided which will enable structural steel members to be easily lifted by a

hoist without danger of slipping. Furthermore, the device can be very easily and quickly applied to a structural steel member so that it can be lifted by the hoist. The apertures 12 may be increased or reduced in number, a plurality being preferably employed for the reason that on lifting light articles the hook is preferably placed in the aperture nearest the arm 11, whereas in lifting heavier articles 10 the hook H will be placed in an aperture more remote from the arm 11.

Various changes may be made in the details of construction without departing from the spirit or scope of the invention as defined by the appended claims.

I claim:

1. A device of the class described comprising a body providing two arms rigidly connected together and arranged at an angle to each other, there being a shoulder adjacent the end of one arm on that side disposed toward the other arm, said other arm being adapted to be lifted by a lifting element and means mounted upon the first mentioned arm 20 for holding the upper part of an object placed upon the shoulder adjacent the first mentioned arm.

2. A device of the class described comprising a body providing two arms rigidly con-

nected together and arranged at an angle to each other, there being a shoulder adjacent the end of one arm on that side disposed toward the other arm, said other arm being adapted to be lifted by a lifting element, there being a slot formed in the first mentioned arm, 30 a locking member slidable in the slot and having its ends wider than the slot, said locking member having an angular end on that side of the arm on which the shoulder is located and which extends towards the shoulder. 40

3. A device of the class described comprising a body providing two arms rigidly connected together and arranged at substantially right angles to each other, there being a plurality of apertures extending transversely through one arm providing for the insertion of a lifting hook, there being a shoulder formed on the other arm adjacent its end on that side disposed toward the first arm, 45 there being a slot formed in the other arm, a locking member slidable therein and held from being withdrawn therefrom, said locking member having an angular end extending 50 toward the shoulder. 55

In testimony whereof I have signed my name to this specification.

CARLTON E. CURRIE.
